UNITED STATES PATENT OFFICE.

ALVA L. HAZELL, OF ROCKDALE, TEXAS.

FOUNTAIN MOP.

Application filed December 12, 1925. Serial No. 75,134.

This invention relates to fountain brushes and articles of like character, and particularly to mops designed to be used upon a floor.

5 One of the objects of the invention is to provide a very simple construction of this kind which embodies a mop proper and a frame within which the mop proper is supported and detachably clamp this frame carrying a spray pipe discharging water upon the mop when desired and having a tubular handle adapted to be connected to a hose.

10 Other objects have to do with the details of construction and arrangement of parts 15 as will appear more fully hereinafter.

My invention is illustrated in the accompanying drawing, wherein:—

Figure 1 is a perspective view of my improved mop;

20 Figure 2 is an under side plan view of the mop by itself;

Figure 3 is an under side plan view of the frame within which the mop shown in Figure 2 is designed to be inserted;

25 Figure 4 is a transverse sectional view showing the mop frame disposed within the supporting frame.

Referring to this drawing, it will be seen that the frame for supporting the mop con-

30 sists of a medially disposed, longitudinally extending member, designated 10, a front member 11, and a rear member 12. The front member is preferably made rigid with the medially disposed member 10 and ex-

35 tends downward therefrom. The rear member 12 is also preferably rigid with the medially disposed portion 10 and extends downward therefrom and is opposed to the front member 11 and is provided with clamp 40 screws 13 or like devices.

Extending longitudinally along the frame and preferably carried by the top member 10 is a spray pipe 14 which is perforated at intervals with spray holes. This spray

45 pipe has removable plugs 15 at its extremities and in the middle is provided with a T 16 from which extends the handle 17, this handle being tubular and having therein the valve 18. The handle extends upward any 50 desired distance and is formed for connection with a detachable hose 19 so that water may be supplied to the tubular handle and thus to the mop.

The mop consists of a rectangular frame 55 adapted to be inserted between the front and side members 11 and 12 and beneath the

member 10. The frame consists of the longitudinally extending side elements 20 and 21 and the end members 22. Mounted in bearings in these end members 22 are the longitudinally extending shafts 23 which are formed at intervals with teeth 24, these teeth being preferably in staggered relation with relation to the teeth of the adjacent shaft. Preferably there are three of these shafts 65 23, each formed with these teeth or lugs 24. The extremities of the shaft carry upon them the gear wheels 25 which mesh with each other, as illustrated, and the central gear wheel is provided with a crank arm 26 having a crank handle. This crank arm permits the central shaft to be rotated and this will rotate the other shafts. The rags or other material which constitute the mop are wrapped upon these several shafts and engaged by the teeth so that the mop material will hang upon these shafts. By rotating the crank handle 26, the cloth forming the mop may be wound up into shape from time to time and the teeth on the shafts keep the 70 cloth from slipping.

75 Preferably the mop frame of the members 20, 21, and 22 is slid into place within the frame formed by the members 10, 11, and 12. This outer frame or casing has a longitudinally extending partition 27 inward of the spray pipe 14, and this partition 27 and the wall 11 are formed with inwardly extending flanges 28 which support the side members 20 and 21 of the mop frame. Thus 80 the water is discharged directly downward in front of the mop and the mop may be readily withdrawn by pulling the mop frame out of its compartment in the same manner that a drawer is pulled out. 95

It will be obvious now that the mop may be used in the manner of an ordinary mop and water may be allowed to flow from the spray pipe 14 onto the floor to any extent required. It may be stated that the scrubbing brush or mop, here shown and consisting of the frame as described is one that is commonly found upon the market, but I have provided a frame within which this scrubbing or mop frame may be mounted 100 and provided means whereby water may be supplied constantly in front of this mop. The mop does away with the necessity of the worker kneeling down upon the floor and scrubbing and does away with the necessity of immersing the mop every now and then in a tub of water. The worker 110

may stand upright and handle the mop effectively and at the same time supply water thereto in any desired quantity, either alternately admitting it or cutting it off by means of the valve 18 or by turning the valve 18 to permit a greater or less flow of water.

While I have illustrated certain details of construction and arrangement of parts, I do not wish to be limited thereto as it is obvious that many changes might be made in these details without departing from the spirit of the invention as defined in the appended claim.

15 I claim:—

A mop of the character described comprising a mop cloth supporting element embodying a rectangular frame and a plurality of mop cloth engaging shafts mounted in said frame and having means where-

by they may be simultaneously and manually rotated, and a frame within which the mop supporting element is adapted to be disposed, comprising front and rear walls, an intermediate partition and a closed top, the partition and one of said walls having inwardly extending flanges on their lower edges, the mop supporting element being adapted to be slid into position between said partition and the other flanged member and rest upon said flanges, a spray pipe extending longitudinally between the partition and the other member of the outer frame and having downwardly discharging perforations, and a tubular handle connected to the spray pipe and having a valve adapted to be connected to a flexible hose.

20 In testimony whereof I hereunto affix my signature.

ALVA L. HAZELL.
